UNITED STATES PATENT OFFICE.

ANTON CIHAK, JR., OF SHELBYVILLE, MICHIGAN.

ONION-TOPPING MACHINE.

1,368,487.

Specification of Letters Patent. Patented Feb. 15, 1921.

Application filed August 26, 1920. Serial No. 406,128.

To all whom it may concern:

Be it known that I, ANTON CIHAK, Jr., a citizen of the United States, residing at Shelbyville, in the county of Allegan and 5 State of Michigan, have invented certain new and useful Improvements in Onion-Topping Machines, of which the following is a specification.

My invention relates to improvements in 10 onion topping machines, and its objects are: first, to provide a means whereby the quantity of work done with the machines now on the market may be greatly increased; second, to provide a means whereby the quality of work will be greatly enhanced, and, 15 third, to provide a means whereby the machine may be "set" to accommodate the "topping" of either large onions, or small onions, as desired.

20 I attain these objects by the mechanism illustrated in the accompanying drawing, in which Figure 1 is a perspective of an ordinary onion topping machine, minus the driving mechanism which I do not deem it necessary to show in this connection, as it forms 25 no part of my invention. Fig. 2 is a side elevation of the upper part of said machine with my improvement in place. Fig. 3 is an end view of the same with the feed tray 30 and the discharge chute removed. Fig. 4 is an edge elevation of my improvement detached from the machine, and, Fig. 5 is a bottom plan of the same.

Similar numerals indicate similar parts 35 throughout the several views.

In the accompanying drawing 1 represents the upper part of an ordinary onion topping machine, 2 being the gutter partitions, 3 the topping rollers, 4 the knives by means 40 of which the tops are removed from the onion, 5 is the discharge chute, and 6 is the feed bin, or bin into which the onions are stored above the topping rollers and knives. All this is old, and in common use in machines of this class, as is, also, a means for 45 "driving" the rollers for topping the onions, hence no showing or description of the power elements is herewith given.

My invention consists in producing a means 50 for holding the onions and onion tops pliably in the gutters over the topping rollers and knives. For this purpose I make use, first, of a sheet metal, or thin wood cover, 7, upon the under side of which I place a pliable 55 pressure element made of tarred paper, rubber, or other equally pliable material, as

shown at 9, one end of each of which is securely connected with the cover, as at 12, while the other end is allowed to sag downwardly from the cover, forming a bow, and is 60 provided with one or more pliable thongs, as 10, that are passed through openings 11 in the cover through which they fit very closely so that the pressure elements 9 may be held 65 in desired positions by friction between the thongs and the edges of the cover adjacent to the openings 11.

As it is necessary to support these elements 70 of my invention higher above the topping rollers than would be possible if the cover 70 rested upon the partitions 2, I use auxiliary partitions 8 which are securely mounted upon the upper edges of the regular partitions, and secure the cover upon the upper edges 75 of the auxiliary partitions, as indicated in Figs. 2 and 3.

With all machines of this class the rollers 3 are presumed to revolve in the direction 80 of the arrows in Figs. 1 and 3, and the longitudinal incline of the knives 4 causes 85 the onions to be moved, gradually, from the receiving, or feed bin, toward the discharge chute, which action is not interfered with by use of my invention, but on the contrary, is so far facilitated as to increase the 90 efficiency of the machine, both as to quantity and quality of work an hundred to an hundred and fifty per cent., cutting the tops much closer to the onions, insuring the cutting of all of the tops from the onions, and 90 at the same time removing much more of the dirt that naturally clings to the onions, leaving them much cleaner and better prepared for marketing.

It will be noticed that my pressure elements 95 extend well down between the gutter partitions 8, 2', and that their relative position may be regulated to meet the demands 100 of the particular onions being treated, by simply adjusting the thongs 10, as hereinbefore stated.

It is understood that there are several 105 different constructions of onion topping machines, some using the longitudinal rollers and knives shown in Figs. 1 and 3, and some of other constructions. I find that my attachment is equally effective upon all stock machines in the market, and, further, that it may be used for a diversity of purposes besides onion topping, as for instance, in the topping of small round beets, 110 and other vegetables.

Having thus fully described my invention, what I claim as new in the art, is:

1. In combination with an onion topping machine having longitudinally positioned, 5 revolving rollers and inclined knives thereon; a cap placed over said rollers and having pliable pressure elements extending downwardly therefrom.
2. In combination with an onion topping 10 machine having partitions thereon forming gutters, revoluble rollers and angularly positioned knives upon said rollers, auxiliary partitions mounted upon the gutter partitions, a cover secured to the upper surfaces 15 of said auxiliary partitions, flexible pressure elements secured at one end to the cover and the other ends bagging downwardly therefrom, and means whereby the bagging ends may be adjusted vertically.
- 20 3. In combination with an onion topping

machine having partitions arranged to form several longitudinally positioned gutters, and revoluble angularly positioned knives located in said gutters; auxiliary partitions mounted upon the gutter partitions, a cover 25 secured to the upper surfaces of the auxiliary partitions, flexible pressure elements secured at one end to the cover and the other ends bagging below the cover between the partitions, the cover having several 30 openings adjacent to the bagging ends of the pressure elements, and thongs connected with the bagging ends of the pressure elements and passed through the openings in the cover to regulate the positions of the 35 pressure elements.

Signed at Shelbyville, Michigan, August 23, 1920.

ANTON CIHAK, JR.
